UNITED STATES PATENT OFFICE

CARL H. LARSON, OF ELKHART, INDIANA, ASSIGNOR TO THE ADLAKE COMPANY, A CORPORATION OF ILLINOIS

ELECTRIC HAND LANTERN

Application filed March 2, 1931. Serial No. 519,428.

This invention relates to electric hand lanterns, and—although the apparatus herein disclosed is suitable for any hand lantern—it is particularly adapted for lanterns used by railway trainmen.

The object of the invention is to produce a simple, rugged, dirt-proof switch which will give unfailing operation under the severe service conditions of railway use.

10 Other objects of the invention will appear from the specification and the appended drawings, in which—

Fig. 1 is an elevation of a lantern embodying one form of the invention;

15 Fig. 2 is a vertical section through the lower portion of the lantern;

Fig. 3 is a vertical section through the lower portion of the lantern taken on the line 3—3 of Fig. 2;

20 Fig. 4 is a transverse section through the lantern on the line 4—4 of Fig. 2;

Fig. 5 is a view similar to that shown in Fig. 2 but illustrating a modified form of the device;

25 Fig. 6 is a sectional elevation through the lower portion of the modified form taken on the line 6—6 of Fig. 5;

Fig. 7 is a transverse section taken on the line 7—7 of Fig. 5.

30 In the embodiment of the invention shown in Figs. 1—4 inclusive, the lantern, generally indicated by 10, comprises a casing 11 having a separable cover 12 and a bail or handle 13 which preferably is made of insulating material. A guard ring 14 forming the base of the device is attached to the casing by means of the legs 15 which are welded or otherwise suitably attached to it and to the skirt 16. The skirt telescopes over the casing

40 as shown in Figs. 2 and 3 and bears against a stop ridge 17 which is rolled into the casing 11. Small machine screws 18, 18 hold the skirt to the casing. The skirt bears an inwardly turned flange 19 which supports an insulating plate 21 and a reflector 22. The skirt, plate and reflector may be held together if desired by the rivets 23. The plate 21 bears metal inserts 24, 24 which are threaded to receive the shell of the lamps 25,

45 50 25 and form lamp sockets.

A battery 26 is inserted in the casing in such a way that its lateral contact 27 bears upon the closed end 20 of the casing and its central contact 28 bears upon a stud 29 which is insulated from the casing by the washers 55 31 and 32.

Electrical connection to the lamps is made by a strip 33 of metal which is held by the riveted head of the stud 29 and bears upon the central contacts of the lamps 25, 25. 60

A spiral spring 34 is attached by the screw 35 to the skirt 16 and has its opposite end held by the handle 36 in the slide 37. The curved ends 38 of the slide 37 bear against the abutments 39, 39 which preferably are 65 molded integrally with the insulating plate 21. The resiliency of the inwardly bent ends of the slide 37 tends to hold the slide firmly against the skirt 16 and prevent infiltration of dirt and other deleterious matter. A 70 locking detent is provided by the shallow depressions 41 and 42 which are molded in the abutments 39, 39 and in which the curved ends 38, 38 of the slide 37 engage. The abutments 39, 39 also serve to space the plate 21 75 from the closed end 20 and since three spacing elements are desirable, the spacer 43 is placed just beyond the path of the spring 34.

The spring 34 is connected through the 80 casing to one terminal of the battery and the sockets 24, 24 are connected through the lamps 25 and contact strip 33 to the other terminal. Accordingly, when the handle 36 is pushed to the side from the "off" position, the spring 34 will be carried against one or the other of the sockets 24, and so establish an electric circuit through the lamp. 85

In the modified form of the device shown in Figs. 5, 6 and 7, peculiarly shaped springs 90 44, 44 are pivoted upon the spacers 45, 45 and have their outer ends hooked through the ends of the slide 46. Since the slide 46 touches the skirt 160, the springs 44, 44 are in electrical communication with the lateral 95 terminal of the battery 260.

The sockets 240, 240 are electrically connected with the central terminal of the battery through the lamps 250, 250 and consequently when the handle 47 is pushed to 100

either one side or the other, either one or the other of the springs 44 will be forced against its co-operating socket and the lamp will be lighted.

5 The spacers 45, forming the pivots for the springs 44, 44 are not concentrically placed with respect to the slide 46 which causes the radius to change as the slide is moved from side to side, and, consequently, 10 it is necessary to put in the bowed take-up portion 48 to compensate for the lengthening of the radius. Preferably, a third spacing plug 49 is molded on the plate 210 so that a three-point bearing is formed, which effectively spaces the plate from the closed 15 end of the casing.

The mechanisms shown are in a dust-tight container and their simple, rugged nature assures the continuous operation of an electric hand signal lantern.

It is understood that the specific embodiments herein shown are for the purpose of illustration only, and that modifications of the switch may be made without departing 25 from the spirit of the invention as defined in the appended claims.

I, therefore, claim as my invention :

1. In an electric hand lantern, a cup-shaped casing of unitary construction adapted to 30 contain a battery, a socket, means for supporting said socket beneath the casing bottom and having a lamp therein, one terminal of which is electrically connected to one pole of the battery and the other to the 35 socket, a conductor member to establish a circuit through the lamp electrically connected to the other pole of the battery and having a free end adapted to slide in a limited arc and a portion adapted to contact 40 directly with the socket when the free end is displaced.

2. In an electric hand lantern, a cup-shaped casing of unitary construction adapted to contain a battery, an insulating plate, 45 means for supporting said plate beneath the bottom of the casing, a socket in the plate having a lamp therein, the central contact of which is electrically connected to one pole of the battery, a spring electrically connected to the opposite pole of the battery having 50 a free end capable of limited movement along the periphery of the device, and a portion of the spring adapted to directly engage the socket, and thereby to establish a circuit through the lamp when the free 55 end is displaced toward the limit of its travel.

3. In an electric hand lantern, a casing having a closed end and adapted to contain a battery having a lateral and a central contact, a skirt electrically connected to the lateral contact surrounding the casing and maintaining an insulating plate in spaced 60 relation to the end of the casing, a metallic socket in the plate having a lamp therein with its central terminal electrically con-

nected to the central contact of the battery, a spring attached at one end to the skirt extending past the socket and having a free end adapted to slide along the circumference of the skirt whereby the spring and socket 70 may be made to touch and an electric circuit through the lamp be established.

4. In an electric hand lantern, a casing having a closed end and adapted to contain a battery having a lateral and a central contact, a skirt electrically connected to the lateral contact surrounding the casing and maintaining an insulating plate in spaced relation to the end of the casing, two metallic sockets in the plate, lamps therein having their central terminals electrically connected to the central contact of the battery, a spring attached at one end to the skirt positioned between and extending past the sockets and having a free end adapted to slide along the circumference of the skirt whereby the spring and either of the sockets may be made to touch and an electric circuit through one of the lamps established.

5. In an electric hand lantern, a casing adapted to contain a battery having an insulating plate maintained in spaced relation to the end of the casing, a socket in the plate, a spring electrically connected to one pole of the battery pivoted on the plate having one end terminating in a laterally extending handle adapted to slide along the periphery of the device and the other end to be forced into contact with the socket and a lamp in the socket having its central terminal electrically connected to the opposite pole of the battery.

6. In an electric hand lantern, a casing adapted to contain a battery having an insulating plate maintained in spaced relation to the end of the casing, a plurality of sockets in the plate, springs electrically connected to one pole of the battery pivoted on the plate having one end adapted to slide along the periphery of the device and the other end to be forced into contact with one of the sockets and lamps in the sockets having their central terminals electrically connected to the opposite pole of the battery.

7. An electric lantern having a casing provided with a closed end and a conductive surface in electrical connection with one terminal of a battery therein, a lamp insulated from the casing and electrically connected to the other terminal of the battery, and a spiral spring having one end electrically connected to the casing and its other slidably along the periphery of the device to complete the electric circuit through the lamp.

8. In an electric hand lantern, a casing having a closed end, a battery in the casing, a skirt fitted over the closed end of the casing maintaining an insulating plate in spaced relation thereto, a socket shell projecting through the plate, a lateral contact on the

battery connected to the casing, an insulated central battery contact projecting through the casing and engaging the central contact of a lamp in the socket, a flexible spring electrically connected to the casing disposed adjacent the socket and external means upon the casing to cause the spring and socket to contact.

10 In testimony whereof I affix my signature.
CARL H. LARSON.
